By Knight Bros.
Attn:

UNITED STATES PATENT OFFICE.

HENRY GOODMAN, OF ST. LOUIS, MISSOURI, ASSIGNOR OF ONE-HALF TO
DANIEL P. KANE, OF SAME PLACE.

LOCK FOR FIRE-ARMS.

SPECIFICATION forming part of Letters Patent No. 288,989, dated November 20, 1883.

Application filed July 28, 1883. (No model.)

To all whom it may concern:

Be it known that I, HENRY GOODMAN, of the city of St. Louis, in the State of Missouri, have invented certain new and useful Improvements in Fire-Arms, of which the following is a full, clear, and exact description, reference being had to the accompanying drawings, forming part of this specification.

This invention relates to a device for adjusting the depth of the firing-notch, so that the gun may be adjusted to pull off with the application of any desired amount of force.

Reference is made to the claims for statement of invention.

15 Figure 1 is a side view of part of a gun with my improvement applied. Fig. 2 is a side view with part of the breech-frame broken away. Fig. 3 is a transverse section at 3 3, Fig. 2, somewhat reduced. Figs. 4 and 5 are perspective views of the eccentric. Fig. 6 is a perspective view of the hammer-hub. Fig. 7 is a perspective view of the adjustable slide by which the depth of the firing-notch is limited. Fig. 8 is an enlarged detail side view of part 25 of the tumbler.

A is the breech-frame; B, the barrel; C, the cock or hammer; D, the hammer-spring; E, the trigger; F, the sear-spring; G, the trigger-guard.

30 H is the pivot-screw upon which the hammer works.

I is a cylindrical block, having bearing in the breech-frame, and through which the hammer pin or screw H passes centrally.

35 J is an eccentric on the inner end of the block, occupying a recess, T, in the side of the tumbler T. The recess has size sufficient to allow the eccentric to be turned around in it.

K is a sliding plate or slide fitting a dovetail 40 groove, L, in the side of the tumbler, and working on a pin, l, that limits the movement of the slide K. The slide K is used to limit the depth of the firing-notch e, for as the trigger-catch e falls into the notch it impinges against the slide K. The position of the slide K in the tumbler is determined by the position of the eccentric J, whose periphery bears against

the inner end of the slide. As means for turning the eccentric is shown a combined thumb-piece and pointer, P, that is moved over a segmental scale, S, whose numbers may indicate the amount of force (in pounds) required to pull off the trigger. The indication in Fig. 1 is that a force of three and a half pounds will be required to pull the trigger. It will be understood that the eccentric remains at rest during the movements of the hammer and trigger.

I claim as my invention—

1. A hammer for fire-arms, having a tumbler 60 formed with a recess inside the firing-notch, and an adjustable plate in said recess to regulate the depth of the said firing-notch, as set forth.

2. In a fire-arm, the combination of a hammer having a tumbler formed with a recess inside the firing-notch, an adjustable plate in said recess, and a recess surrounding the pivot-pin, and a cylindrical block having bearing in the breech-frame, provided with an eccentric at its inner end to occupy the recess in the hammer surrounding the pivot-pin, the said block being turned to adjust the plate by means of the eccentric to regulate the depth of the firing-notch, as set forth.

3. In a fire-arm, the combination of a hammer having a tumbler provided with an adjustable plate inside the firing-notch, and a cylindrical block having an eccentric on its inner end to adjust the plate, and a pointer at 80 the other end to indicate the position of the plate and depth of the firing-notch, as set forth.

4. In a fire-arm, the combination, with a hammer having a tumbler provided with an adjustable plate to regulate the depth of the 85 firing-notch, and a cylindrical block having an eccentric to adjust the plate, and an indicator or pointer, of the frame provided with a scale, as set forth.

HENRY GOODMAN.
